UNITED STATES PATENT OFFICE

HANS LUEDTKE, OF BERLIN-TEMPELHOF, GERMANY

ORCHESTRAL INSTRUMENT

Application filed December 4, 1931, Serial No. 579,085, and in Germany December 16, 1930.

This invention relates to an orchestral instrument with one or more keyboards, the new feature of which is that when touching several keys of an organ-like keyboard, 5 different sound characters can be played simultaneously for each key.

This instrument has the advantage that, for example, the ten-keyed touch of a player on a single keyboard produces ten different 10 tone colours separate from one another, and that the player can freely alter each tone colour while playing by means of free switches.

In organ-like playing and registration 15 there has hitherto been only the following fundamental rule: If, for example, three tones are played on the same organ manual, and if, at the same time, the flute stop is drawn, three tones of the same sound character, namely, "flute" are produced so that all the three tones belong to a common 20 "sound producing plane."

If the organist wishes to play three different sound characters, such as, for instance, 25 oboe, violin and flute quite independently, he must play with two hands on three manuals.

According to the present invention the organist must be able to play any desired 30 number of sound characters independently of one another on a single keyboard. The following cases which are already known in organ playing do not affect the present invention.

(a) The double touch with its deeper second touch corresponds to a second manual lying below the normal keyboard. With the double touch it is only possible to add two 35 tone colours or strengths of tone and not to differentiate them.

(b) Organ stops of great compass are, it is true, subject to a gradual change in the construction of the pipes and in the tone colour in the course of their series of pipes, 40 but this change is rigidly fixed by the organ builder so that an organist cannot play at once two neighbouring tones with different sound characters.

(c) Treble couplers or bass couplers or 45 similar arrangements in organs do not allow

of a free sound separation of adjacent tones. In treble couplers only an octave of the highest tone played on one manual is coupled over from another manual.

In bass couplers the same applies to the 55 lowest tone played. If both couplers are used there is a difference between the bass tone, the middle parts, and the treble tone, but there is no complete separation of sound.

In the accompanying drawings the invention is illustrated diagrammatically in one constructional example.

Fig. 1 shows how the depression of three keys on a keyboard causes production of sound in three different sound planes. 65

Fig. 2 shows how one of two tones played together on a keyboard is produced in only one sound plane while the other is produced simultaneously in two planes.

Fig. 3 shows how fixed stages prepared for 70 different sound devices are established, and

Fig. 4 shows a diagrammatical view of the instrument.

1. Sound medium

The following come within the scope of 75 the new instrument.

(a) All the sound media known in organ playing such as can be released electrically by means of wind chests with pipes, reeds, 80 noise effects, and the like.

(b) Sounds produced radio-electrically or optic electrically with an indirect electrical method of playing and registration.

(c) Separate sounds on films, disc records 85 or magnets as well as series of microphones which are employed for kinematographic recording of such sounds as long as this can be played and the registration effect indirectly by electric means.

2. Electrical playing and drawing of stops

The nature of electrical keyboard operation and electrical registration aids and the like with all variations of the system is generally known in organ building. 95

3. Key, keyboard, registration aids, console works

In order to produce a sound by pressing 100 a key, at a definite pitch and with definite

sound character, as in modern organs, the organist must have a "console" which is connected by electrical cables with the source of sound, the "works." The console has one or more keyboards with their keys and all the necessary registration aids.

4. *Sound producing plane, abbreviated "sound plane"*

10 This name will be applied in connection with the new instrument to every union of "sound devices" (see below) which is able to produce a tone of definite sound character.

15 The following have to be achieved by means of the technical means under 1-4.

Sound separation (Fig. 1)

There is to be a sound separation between neighbouring tones of a keyboard which are 20 played together which for each key separately from the others simultaneously with determining the pitch releases one or more sound planes belonging only to this key.

25 Fig. 1 shows an example of the sound separation with three keys or three tones a' , f' , d' , which are played on one keyboard but are required to operate on three different sound planes indicated with I, II and III. Further tones could be simultaneously played 30 in the sound plane IV and in any number of other sound planes.

For each sound plane as many relay connections are provided as there are keys on the keyboard. The mode of operation of 35 the relay connections can be seen in Fig. 1, sound plane II above the key f' . The same reference letters are to be assumed for all relay connections.

If the instrument is not played, all contacts A, J, L as well as the contacts M and N of the relays have a voltage applied.

When, on the other hand, the instrument is played, that is when a key is pressed, the current flows from B to C in the following 45 manner for the tone a' played:

The current flows from B through the contact A of the relay belonging to the key a' in the sound plane I, and from there through the coil S of this relay and the contact of the key a' to C.

Owing to the electromagnetic action, the armature of the relay shoots up and connects J with K but interrupts the connection A—L and that from M—N whereby:

55 (1) All the relays of the sound plane I for sounds deeper than a' are without current further.

(2) All the other coils S which connect the key a' with the other sound planes are 60 without current and

(3) The current from B flows through K in sound plane I, which is short circuited with J—D, that is, to the various sound devices of the sound plane I.

65 If in addition to the key a' a lower key,

for example, f' is pressed simultaneously, the above process applies for a' .

In addition the same process is repeated for f' as the second tone played which will therefore only be connected with a single 70 sound plane, namely, the sound plane II. The current now flows from B through contact A of the relay belonging to the key f' in the sound plane II, from there through the coil S of this relay to the contacts N and M of the relay belonging to the same key f' in the sound plane I, and then over the closed contact of the key f' to C. The armature of the relay in the sound plane II is attracted and the connection described for the sound plane I is now repeated for the tone f' in sound plane II. This process can be arranged for any desired number of tones or sound planes.

Sound plane coupling (Fig. 2)

85 The term "sound plane coupling" designates a special method of employing the sound separation. For, contrary to Fig. 1, by a different construction of the relay and 90 a different manner of conducting the current several sound planes can be operated simultaneously by means of one key with any desired difference from the other keys. This gives a new kind of coupling in organ technique. Fig. 2 shows an example of this.

Fig. 2 shows that when the key a' is depressed, the sound plane I is operated, while, when the keys a' and f' are depressed simultaneously, the upper key a' operates on the sound plane I and the lower on the sound planes I and II simultaneously. When three keys are depressed, the uppermost key a' operates the sound plane I, the middle key f' , the sound planes I and II and the lowest 105 key d' sound planes I, II and III.

The mode of operation for Fig. 2 is as follows:

When the key a' is depressed, the current 110 flows through both relay coils S, O of sound plane I. The relay armatures are attracted and break the connection:

(1) From A—L so that all the coils of the lower keys of the sound plane I are without current and

(2) From M—N so that all the coils S of the other sound planes beginning at II are without current.

On the other hand J is short circuited with K so that current flows from B through J, K, D to the sound devices Fig. 3.

If in addition to the key a' the key f' is also depressed, current flows through the coil S of the sound plane I for f' also and also through the coil S of the sound plane II through M, N of the sound plane I. For sound plane II, however, the process is exactly the same as for tone a' in sound plane I. Consequently f' sounds in sound planes I and II, but a' only in sound plane I.

Fig. 2 shows also a blank switch *i* in the position of rest which locks the contacts *J* and *K* so that it can occupy an existing sound plane without, however, being able to release its sound device.

Any number of blank switches *i* may be provided, as is the case with the sound keys. The sequence between the two may be mixed as desired. The spatial arrangement will be 10 according to practice. The blank switches *i* in Fig. 2 could also be imagined as disposed outside the row of sound keys in a separate row below the sound keys. With the aid of blank switches *i*, any kinds of original coupling effects between the separate sound planes can be imagined, for example, as follows:

The uppermost key *a'* sounds only in sound plane I, the second key from the top, being 20 a blank switch *i*, switches on the blocking devices but does not sound. The third key from the top, *f'*, sounds in the sound planes I, II and III. The fourth key from the top being a blank switch *i* only operates the 25 blocking members and does not sound. The fifth key from the top being a blank switch *i* only operates the blocking organs and does not sound. The sixth key *d'* sounds in sound planes I-IV.

Above the highest tone *a'*, three blank switches *i* may also be employed so that the sound planes I, II and III are occupied and the chord *a', f', d'* would sound as follows:

a' as the highest key sounds in sound planes I-IV. *f'* as the second key sounds in sound planes I-V, and *d'* as the third key sounds in sound planes I-VI. By such variations in the conduction of the current, various kinds of couplings are conceivable, 40 of which Fig. 2 only shows a constructional example.

The sound separation or sound coupling described above is to be combined according to the new process with a registration system operating simultaneously. In order that this co-operation can be explained with reference to Figs. 3 and 4, the following expressions must first be explained:

50

5. Sound device

Each sound plane has a number of sound devices, the combined action of which determines its sound character at any moment. 55 Only the simultaneous combined action of the sound devices in the various sound planes produces the sound of the complete action.

A single sound device would be, for example, the sound scale of a flute series of 60 organ pipes, generally called flute stop.

Other sound devices are, for example, the swell box of an organ, a tremulant, a coupler, an adjustable radio condenser, a radio potentiometer, or a potentiometer used with 65 a sound record on a film, and the like.

6. Contact scale

This term is applied to each combination of electrical contacts which is provided at any time for a sound device.

A sound device such as an organ, flute stop has, for example, the contact scale: "on-off"; a sound device tremulant, for example, "slow, medium, rapid"; a sound device potentiometer or swell box, for example, stages 1-10 or a gradually sliding scale; a sound device "registration cylinder addition" of an organ, for example, 20 or 30 steps.

In this case it is immaterial whether the 80 separate steps of these contact scales refer to a progressive addition or to a mutually releasing change.

7. Fixed stage

This indicates the contact stage, to which 85 the contact scale of a sound device is adjusted in each case.

A sound device such as the flute stop, for example, can only be either on or off; a sound device such as the swell box with 10 90 stages can have only one of these, for example, the stage 6 switched on so that in this case stages 1-6 would be operative.

8. Total constellation

This indicates a simultaneous complete preparation of fixed stages for all the desired sound devices which can be obtained by means of a trigger or a button or the like. It is immaterial whether these fixed 100 stages are provided by the builder in the action, or are only prepared by the player. Several such "total constellations", of course with different contents, must run parallel to one another and mutually release one another in a manner known in organ building. Accordingly, such a "total constellation" is analogous to the nature of a fixed or freely adjustable organ combination. There are, however, the following differences:

(a) The idea of the "total constellation" is not regarded as new in itself, but the co-operation of "sound separation" and the simultaneously prepared registration aids.

(b) The organ combination applies as a rule to all the manuals or keyboards at once, and at least have a whole organ manual. The "total constellation" according to the invention applies also to the relation of adjacent chord tones within a single keyboard.

(c) In organ building not all sound devices are completely fixed even when they are prepared in a fixed or freely adjustable combination.

In an organ with two or three swell boxes, for example, the swell boxes themselves, are never included in the combination. It is a feature of a "total constellation", however, that in each case all the desired sound devices without exception are prepared in fixed 125 130

stages. In an action with three swell boxes, a fixed stage should accordingly be provided in a "total constellation" for each swell box (Figs. 3 and 4).

5 The following effects are to be obtained with the technical means described under 5-8.

Simultaneity of registration (Figs. 3 and 4)

10 The sound separation is connected with a "simultaneity of registration" for all existing sound planes, which is effected in any desired number of "total constellations", which are mutually releasable by means of 15 prepared fixed stages. Fig. 3 shows as an example two "total constellations" P and Q. For constellation P all the fixed stages can be switched on simultaneously by means of the press button T. For constellation Q the 20 switching on is effected from press button U. The two press buttons T and U can be mutually released in a known manner by means of the contact Z.

According to Fig. 3, constellation P is 25 switched on and shows, as prepared in sound plane I, tone a':

Sound device "4' Uf." (abbreviation for organ stop unit flute 4')

Sound device "16' Uo." (abbreviation for 30 organ stop unit oboe 16')

Sound device "W" ("W" means well box), on fixed stage 3 of its contact scale.

In the other sound planes of constellation P further sound devices are to be imagined 35 as prepared on other fixed stages which are not shown in Fig. 3.

After the preparation which is effected either by the builder or by the player, the press button T is pressed and thereby the 40 "total constellation" P is switched on. In a similar manner the various fixed stages are also to be imagined as prepared in constellation Q of Fig. 3 for all sound planes.

As the player previously released the constellation P by means of the button T he 45 can now, by means of the button U, release simultaneously all the fixed stages of the constellation Q while P disappears. Consequently any desired change between any desired number of constellations with any desired contents for each sound plane can be 50 constantly effected while playing.

Diagrammatic general view (Fig. 4)

55 The example according to Fig. 4 shows a diagrammatic general view. By the selection of the sound media chosen here, it is only intended to demonstrate the difference of the possible contents without bringing 60 up any musical problems.

Two constellations P and Q are assumed to have been prepared for three sound planes which is most clearly shown in tabular form.

65 The abbreviations in Fig. 4 mean the following:

"Wi I":—Wind-chest for organ-pipes in sound plane I,

"Ra II":—Radio-electrophone in sound plane II,

"Li III":—Sound-on-film fixing series of 70 sounds in sound plane III,

"Th.":—Pitch of tone,

"W":—Number 1 to 4 swell-box stations,

"Fr I, Fr II, Fr III":—Free switches (see 75 below)

"4' Uf":—"Unit flute 4'" (organ stop),

"16' Uf":—"Unit flute 16'" (organ stop),

"8' Uo":—"Unit oboe 8'" (organ stop)

"16' Uo":—"Unit oboe 16'" (organ stop)

"W 7": tremolo, (organ sound device) 80

"x":—"on" (switched on)

"y":—"off" (switched off)

"z":—Mutual release between U and T.

"Dk II":—Adjustable condenser for changing the tone-colour line of an electro- 85 phone.

"Fo II":—Potentiometer for changing the strength of tone of an electrophone.

"Vz III":—Distortion scale of a sound-on- 90 film apparatus.

"Ap III":—Amplitude scale of a sound-on-film apparatus.

Consequently, Fig. 4 shows the following:

Type of sound media	Sound devices assumed to be existent	Contents of the contact scale	Fixed stage in constellation P	Fixed stage in constellation Q	95
Wi I Sound plane I Key a'	4' Uf 16' Uf 8' Uo 16' Uo W1-W6	On/off On/off On/off On/off Stages 1-6	On Lacking Lacking On Fixed stage 3	Lacking On On Lacking Fixed stage 4	100
Ra II Sound plane II Key f'	Dk II Po II	5 stages 5 stages	Fixed stage 4 Fixed stage 2	Fixed stage 3 Fixed stage 5	105
Li III Sound plane III Key—	Vz III Ap III	5 stages Sliding scale	Fixed stage 5 1st quarter	Fixed stage 2 3rd quarter	110

Free switches Fr (Figs. 3 and 4)

The free switches Fr. I, Fr. II and Fr. III in Fig. 4 with the points (not shown) of the conductor R and their buttons x (on) and y (off) represent the separate playing 115 media, which, by electrical operating means, lead directly from the console to each sound device, that is, not through a prepared constellation (P or Q). By means of the free switches the player can switch on or off units freely the contact scales provided for all the sound devices, and therefore can arrange his registration as desired.

Each free switch has as many switch contacts as the sound device belonging to it has fixed stages. The free switches can be operated by hand or foot.

If a sound device is already at a definite fixed stage during an adjusted total constellation, for instance if a swell box with 120

10 stages is fixed at stage 3, the stages 1-3 are ineffective for the free switch in question. The remaining stages 4-10 can be controlled freely by the player. Accordingly the fixed stages of each sound device form a variable "zero foundation" according to the total constellation for the remaining free registration on the part of the player.

What I claim is:

10 1. An orchestral instrument having a plurality of key-boards each comprising a number of keys, a plurality of sound producing devices capable of being arranged in different groupings, each grouping having a different tone quality, and a system of relays for each key, each relay of which when energized connects the key with a plurality of said groupings, the arrangement being such that when a plurality of keys are depressed simultaneously a different tone quality is produced by each key.

20 2. An orchestral instrument as claimed in claim 1, the arrangement being such that when a plurality of keys are depressed si-

multaneously each is connected to a single grouping, and no two keys are connected to the same grouping.

3. An orchestral instrument as claimed in claim 1, the arrangement being such that when a plurality of keys are depressed simultaneously each is connected to a different number of groupings.

4. An orchestral instrument as claimed in claim 1 having a plurality of blank switches, and a system of relays for each switch, the arrangement being such that when a switch is actuated it occupies a plurality of groupings and prevents said plurality of groupings being connected to a key for the production of sound.

5. An orchestral instrument as claimed in claim 1, and having free switches adapted to connect sound producing devices directly to the console, whereby the registration can be varied independently of the arrangement of the sound producing devices in groups.

HANS LUEDTKE.
